UNITED STATES PATENT OFFICE

CHARLES W. TROW, OF SOUTH READING, MASSACHUSETTS, ASSIGNOR TO
CYRUS WAKEFIELD, OF SAME PLACE.

IMPROVEMENT IN RATTAN MACHINERY.

Specification forming part of Letters Patent No. 35,859, dated July 8, 1862.

To all whom it may concern:

Be it known that I, CHARLES W. TROW, of South Reading, in the county of Middlesex and State of Massachusetts, have invented certain new and useful Improvements in Machinery for Cutting Strands from Rattan for Caning or Seating Chairs and for other Purposes; and I do hereby declare that the following is a full, clear, and exact description of the same, reference being had to the annexed drawings, making part of this specification, and in which—

Figure 1 is a side, Fig. 2 a sectional, and Fig. 3 a plan, view of my improved machine. Figs. 4, 5, 6, 7, and 8 are details of some of the parts, drawn to a larger scale to show more clearly their construction.

The letters of reference indicate like parts in all the figures.

The subject-matter of this (my invention) is a machine in which all the operations requisite to prepare the strands of rattan or cane for chair-seating or other purposes shall be effected successively—that is to say, the object of my invention is to perform the operations of removing the knots or excrescences upon the rattan, the splitting or dividing of its surface into separate parts or strands, of dressing and finishing the said strands to the proper form, and of removing them from the core, all successively and continuously in one machine, so that the rattan entering at one end shall issue at the other into strands perfectly dressed and finished and adapted to be used in seating chairs and for other purposes, together with a core which may be used for coops or for the manufacture of baskets, or for other similar purposes.

My improvements relate to that kind of machinery in which the surface of the rattan is first divided into longitudinal sections by cutting the stick or cane to a requisite depth and by then separating said sections from the core to form strands; and my invention consists, first, in the employment, in combination with feeding-rollers, of a series of self-adjusting scraping-knives operating, as hereinafter described, to close against the surface of the rattan, whatever its diameter may be, and yield to all inequalities other than the knots or excrescences; second, in the use, in combination with a suitable feeding mechanism, of a series

of marking-knives with which are combined two cutting-edges, forming an angle more or less acute, according to the number of strands to be cut from each stick; third, in the combination, with knives provided with dressing cutting-edges, of a tubular coring-cutter; fourth, in the combination and arrangement of the apparatus herein described, performing the several operations of dressing, splitting, coring, and finishing the rattan successively and continuously in one machine, as hereinafter described.

A is the frame of the machine, upon which the several parts thereof are arranged.

B is the scraper-head. It is made of iron or other material, of a circular or of such other convenient form as to receive the scraping-knives and the parts with which it is combined to effect their self-adjustment, as hereinafter described. The whole is mounted on a horizontal sleeve, E, by which it is secured to the frame in suitable journals, G. The knives C are curved, as shown in Fig. 2, and are held in their stocks D by means of set screws f, passing through bridles i. The number of knives may vary according to circumstances. In the accompanying drawings I have shown four, and they are disposed radially upon the disk B, and hung or pivoted by means of pins k, in slots cut in their side supports, H. This mode of hanging of the blocks, in combination with the springs h, bearing upon their tops, enables them to converge or diverge according to the size or diameter of the cane. Behind each block there is another spring, g, the office of which is to throw forward the inner ends of the blocks, and thus hold the knives expanded (see Fig. 5) until closed by coming in contact with the rattan moving in the directions of the arrows x y z.

The scraping-knives are otherwise of ordinary construction and operate substantially in the manner as those heretofore in use. The rattan is fed to the scraper by passing through the sleeve I, between the pair of feed-rollers R, to which equal rotary movement is imparted by means of an endless screw and spur-wheel arrangement, or by some other means of transmitting motion. The rattan thus fed to the scraper is carried through and from it by being seized by the feed-rollers R', which latter

carry it forward to the rolls *r*, that securely guide it to the marking, splitting, and dressing knives *F*, of which I will now proceed to give a particular description: They are made in the form shown in perspective in Fig. 6 and in front and side elevation in Figs. 7 and 8, respectively. There are three cutting-edges—two, *v* and *w*, in front and one, *t*, underneath—the two former forming an angle the apex of which coincides with the latter. The angle between the two front edges varies in accordance with the number of strands to be cut on each rattan, and they are arranged in such relative order as that each front edge of any cutter shall be parallel with the front edge of the next following on either side, and so that each strip or strand shall have its side dressed by parallel cutters. To illustrate, I will suppose that the surface of the rattan is to be divided into four strands. The cutters used in accordance with my invention would be angular **V** or plow cutters, the front cutting-edges of which form an angle of ninety degrees, the said cutters being arranged at equal distances from each other and concentrically in relation to a common circle.

In Figs. 1, 2, and 3 I have shown, the cutters arranged upon a cone, *K*, which is set on a horizontal sleeve, *L*, through which the marked or scored rattan is fed by means of the feed-rollers *R* to a tubular cutter, *M*, which is of such diameter as to core the stick, leaving strands of requisite thickness that are stripped and carried off along the inclined plane *N*, while the core issues at the end of the cutter at *O*.

From the above description of the construction and arrangement of the parts and their combination as a whole, it is obvious that the same is susceptible of many modifications without departing from the principle of my invention. Thus the **V** or plow cutters, instead of being arranged in front of the tubular cutter, may be placed around or form part of it.

Having thus fully described my invention and the manner in which the same is or may be carried into effect, I shall state my claims as follows:

1. The employment, in combination with feeding-rollers, of a series of self-adjusting scraping-knives constructed, arranged, and operating, as herein described, to close against the surface of the rattan, whatever its diameter may be, and yield to all inequalities other than the knots or excrescences, as set forth.

2. The angular marking and dressing knives, in combination with the feeding mechanism of rattan machinery, substantially as described.

3. The combination, with the knives provided with the dressing cutting edges, of a tubular coring-cutter, arranged substantially in the manner and for the purposes set forth.

4. The combination and arrangement of the apparatus herein described, performing the several operations of dressing, splitting, coring, and finishing the rattan successively and continuously in one machine, in the manner as herein set forth.

C. W. TROW.
